UNITED STATES PATENT OFFICE.

ANTONIO AUGUSTO BARBOSA, OF LOS ANGELES, CALIFORNIA, ASSIGNOR OF ONE-FOURTH TO RALPH J. DOMINGUEZ AND ONE-FOURTH TO WILLEDD ANDREWS, BOTH OF LOS ANGELES, CALIFORNIA.

MARINE MUNITION AND THE LIKE.

1,278,420.

Specification of Letters Patent. Patented Sept. 10, 1918.

Application filed April 12, 1918. Serial No. 228,204.

To all whom it may concern:

Be it known that I, ANTONIO AUGUSTO BARBOSA, a citizen of the United States, residing at Los Angeles, in the county of Los Angeles and State of California, have invented new and useful Improvements in Marine Munitions and the like, of which the following is a specification.

This invention relates to marine munitions and the like, and it has for its object to provide improved means and instrumentalities of this character, for the purpose of attacking and destroying marine vessels, which will be superior in point of relative simplicity and inexpensiveness in construction and organization, taken in connection with facility in use and control, positiveness and effectiveness in operation, and general efficiency.

With the above and other objects in view, the invention consists in the novel and useful provision, application, construction, combination, association, relative arrangement and mode of handling and use of such means and its parts and features, all as hereinafter described, shown in the drawing and finally pointed out in claims.

In the drawing:

Figure 1 is a detail view of an improved mine constructed and organized in accordance with the invention, parts being broken away for clearness of illustration;

Fig. 2 is a detail transverse sectional view of the same, taken upon the line x^2-x^2 , Fig. 1, and looking downwardly;

Fig. 3 is a view similar to Fig. 1, showing a modified form of construction intended for a different mode of use, a part being broken away for convenience of illustration;

Fig. 4 is a conventional showing of a submerged submarine craft provided with two of the mines shown in Fig. 1, said mines being shown upon an enlarged scale, and connections between the mines and the submarine being broken away for convenience of illustration. This view also shows a marine vessel above the mines and about to be attacked by the same;

Fig. 5 is an enlarged detail transverse sectional view taken upon the line x^5-x^5 , Fig. 4; and

Fig. 6 is a view similar to Fig. 4, of a submarine and mine features therewith, showing the mines being towed by the submarine, parts being broken away for convenience of illustration.

Corresponding parts in all the figures are designated by the same reference characters.

Referring with particularity to the drawing, the improved marine munitions therein shown, in each of the figures in which the same appear, comprise a mine A, the same being provided in Fig. 3 with firing means a responsive to contact with a ship or other object, and being provided in the modification shown in Figs. 1, 2, and 4 with firing means b adapted to be controlled from a point remote from the mine A, as from the submarine B with which such mines are connected as by cables c . The mine shown in Fig. 3 is provided with a depending anchorage chain 7 leading to an anchorage 8 whereby the mine is held in position beneath the surface of the water and exposed to contact by ships and other objects.

In each instance the mine comprises a lower or main casing member 9 and an upper casing member 10, preferably rounded or dome-shape, and bolted to the lower casing member 9 at co-engaging flanges, as at 11. Within the casing members is provided the explosive charge 12, which is disposed within an envelop of pliable or plastic or semi-mobile substance, 13, grease of suitable consistency being especially adapted for such use.

Within the mass of explosive material 12, and preferably above the zone of the flange 9 connection at 11, is provided a mass 14, of suitable percussive material or fulminate, melinite being found suitable for such agent. This likewise is disposed within or covered over by an envelop 15 of the same general character as the envelop 13, and preferably of grease. In the form of mine shown in Fig. 3 the firing means a comprise

firing pins 16 which are slidably mounted in tubes or sleeves 17 preferably detachably applied to the upper member 10 of the casing, by threaded connections as at 18, at openings in such casing member 10, which permit the pins to play lengthwise and to be brought at their inner ends into contact with the percussive material or high explosive 14, such pins being yieldingly withheld slightly from the fulminate 14, as by contractile springs 19 applied to the pins and wings.

In the form of mine shown in Figs. 1, 2, 4 and 6, I provide the firing means *b* utilizing an electric spark produced at the fulminate 14 by an electric path consisting of circuit wires 20 provided within the cable *c* and suitably insulated apart as at 21, such circuit wires leading to the battery or source of electrical supply 22 controlled by a suitable switch 23, the battery and switch being installed, in the particular arrangement and utilization shown in the drawing, upon or in the submarine vessel *B*.

The mine at its lower member 9 is preferably provided with vertical or longitudinal reinforcing flanges 24, which may be joined together by staggered or zigzag cross flanges 25.

D designates a marine vessel, such as a war ship, beneath which the submarine *B* with its captive mines *A* is located, and which is about to be attacked by the same.

The operation, method of use and advantages of the improvements in marine munitions will be readily understood from the foregoing description, taken in connection with the accompanying drawing, and the following statement:

The contact mine shown in Fig. 3 is suitably located and anchored and operates under the same conditions as in ordinary use of such marine mines, and the inclusion of the fulminate mass 14 and of the explosive mass 12 in plastic or greasy envelopes 15 and 13, causes a highly efficient control and application of the energy released upon firing of such charges. The action seems to be to cause a more evenly distributed and uniformly directed radiation of the explosive forces. In the use of these mines in proximity to each other, the envelopes of plastic substance or grease prevent sympathetic explosion of the mines when it is intended to only discharge one. This is particularly useful in the event that two or more mines are held captive by a submarine or other vessel as shown in Figs. 4 and 6, and intended to be successively or independently discharged. The use of these grease envelopes seems to prevent such sympathetic explosions due to concussion.

The reinforcement flanges 24 and 25 serve to relatively strengthen the lower member 9 of the casing, and thereby tend to cause

the disruption of the casing at its upper member 10, whereby the force of the explosion is directed upwardly and laterally rather than directed downwardly.

It is manifest that many variations and adaptations of my invention may be made without departing from the spirit of the invention or the terms of the following claims.

Having thus disclosed my invention, I claim and desire to secure by Letters Patent:

75

1. In improvements of the character disclosed, a mine comprising an outer shell or casing, explosive material within the casing, and an envelop of plastic substance within the casing and surrounding the explosive material.

2. In improvements of the character disclosed, a mine comprising an outer shell or casing, explosive material within the casing, and an envelop of plastic substance within the casing and surrounding the explosive material; there being provided within the explosive material a mass of suitable fulminate.

3. In improvements of the character disclosed, a mine comprising an outer shell or casing, explosive material within the casing, and an envelop of plastic substance within the casing and surrounding the explosive material; there being provided within the explosive material a mass of suitable fulminate, and there being provided an envelop of plastic material surrounding such fulminate.

4. In improvements of the character disclosed, a mine comprising a shell or casing, explosive material within the casing, and an envelop of grease surrounding the explosive material.

5. In improvements of the character disclosed, a mine comprising a casing, explosive material within the casing, and a body of plastic material interposed in part between the casing and the explosive material.

6. In improvements of the character disclosed, a mine comprising a casing, explosive material within the casing, and a body of plastic material interposed in part between the casing and the explosive material; there being provided a mass of fulminate within the explosive material which is likewise in part surrounded with a mass of plastic material.

7. In improvements of the character disclosed, a mine comprising a shell or casing, explosive material within the shell or casing, and a mass of grease disposed in part between the shell or casing and the explosive material.

8. In improvements of the character disclosed, a mine comprising a shell or casing, explosive material within the shell or casing, and a mass of grease disposed in part

between the shell or casing and the explosive material; there being provided a mass of fulminate within the explosive material and a mass of grease disposed in part between the fulminate and the explosive material.

9. In improvements of the character disclosed, a mine comprising a shell or casing one portion of which is provided with flanges by which it is reinforced to strengthen it over a further portion, and explosive material within the shell or casing.

10. In improvements of the character disclosed, a mine comprising a shell or casing one portion of which is reinforced to strengthen it over a further portion, and explosive material within the shell or casing; there being provided between the portion of the casing of lesser strength and the explosive material a mass of plastic sub-
stance.

11. In improvements of the character disclosed, a mine comprising a shell or casing one portion of which is reinforced to strengthen it over a further portion, and explosive material within the shell or casing; there being provided between the portion of the casing of lesser strength and the explosive material a mass of plastic sub-
stance, and there being a mass of fulminate disposed within the explosive material and

within the portion of the casing of lesser strength.

12. In improvements of the character disclosed, a mine comprising a shell or casing one portion of which is reinforced to strengthen it over a further portion, and explosive material within the shell or casing; there being provided between the portion of the casing of lesser strength and the explosive material a mass of plastic sub-
stance, and there being a mass of fulminate disposed within the explosive material and within the portion of the casing of lesser strength; there being a mass of plastic sub-
stance disposed in part between the explosive material and said fulminate.

13. In improvements of the character disclosed, a mine comprising a shell or casing, part of which is reinforced to strengthen it over a further portion and cause the force of the explosion to be directed upwardly and laterally rather than downwardly, and explosive material within the shell or casing.

In testimony whereof, I have signed my name to this specification in the presence of two subscribing witnesses.

ANTONIO AUGUSTO BARBOSA.
